WHEEL

Filed Jan. 31, 1923

Inventor
WALTER F. KASPER

By *Paul, Paul & Moore*
ATTORNEYS

Patented Nov. 11, 1924.

UNITED STATES PATENT OFFICE.

WALTER F. KASPER, OF FAIRMONT, MINNESOTA, ASSIGNOR TO FAIRMONT GAS ENGINE & RY. MOTOR CAR CO., OF FAIRMONT, MINNESOTA, A CORPORATION OF MINNESOTA.

WHEEL.

Application filed January 31, 1923. Serial No. 616,065.

To all whom it may concern:

Be it known that I, WALTER F. KASPER, a citizen of the United States, resident of Fairmont, county of Martin, and State of Minnesota, have invented certain new and useful Improvements in Wheels, of which the following is a specification.

The object of my invention is to provide a wheel composed of a rim and a hub-supporting member pressed preferably from sheet metal and rigidly secured together to form a light but strong and durable two-piece wheel and one that is particularly adapted for railway motor cars.

15 A further object is to provide a wheel of the type described which can be easily and quickly assembled and when one member becomes worn or broken can be taken apart and a new piece substituted for the worn or 20 broken member, thereby avoiding the necessity of throwing the entire wheel aside.

Other objects of the invention will appear from the following detailed description.

The invention consists generally in various constructions and combinations all as 25 hereinafter described and particularly pointed out in the claims.

In the accompanying drawings forming a part of this specification,

30 Figure 1 is a side view of a wheel embodying my invention;

Figure 2 is a sectional view on the line 2—2 of Figure 1.

In the drawing, 2 represents the rim of 35 the wheel formed of one piece of metal, preferably sheet steel, pressed into a circular form with a rail flange 3 provided on one edge. At the other edge of the rim, an inwardly turned flange 4 is formed extending preferably around the wheel. A hub 5 is provided having a bearing 6 for the axle, and a radial flange 7 provided preferably intermediate to the ends of the hub. A sheet metal support 8, preferably of pressed steel, 40 has a shoulder 9 formed in its outer portion to receive the edge of the flange 4; the outer edge of said support being seated on the inner surface of the flange and rigidly secured thereto by suitable means such as bolts 10. 45

50 From a point near the shoulder 9, the sup-

port 8, preferably disc-like in form, and forming the spokes of the wheel, extends obliquely to the center, and near the center has an annular flanged portion 11 enclosing a central opening through which the hub 55 projects, said flanged portion being seated against the annular flange 7 and rigidly secured thereto by suitable means such as rivets 12.

For the purpose of strengthening the sheet 60 metal support, to resist crushing stresses, I prefer to provide a series of radially extending ribs 13 pressed in the metal when the support is formed; said ribs forming correspondingly shaped grooves on one side in 65 which lugs 14 provided at intervals on the flange 7 are seated, thereby locking the hub and its support against a relative rotary movement. The support also has openings 15 therein extending radially; these openings being formed when the plate is pressed 70 out, and reducing to some little extent the weight of the wheel and the amount of metal in the hub supporting plate.

The advantages of this type of wheel will 75 be immediately apparent. In case of wear or breakage of the rim, the bolts 10 can be easily and quickly removed and a new rim substituted for the worn one, without the necessity of casting the entire wheel aside. 80 The parts being pressed by means of suitable dies, the wheel sections will all be interchangeable and the wheels can be quickly and easily assembled without adjusting or fitting.

85 I claim as my invention:

1. A wheel comprising a metal rim having an inwardly turned flange, a plate having an outer edge seated against said flange, and a shoulder to receive the edge of said flange, said plate extending diagonally from a point near said flange to the center of the wheel and having a central orifice, and a hub mounted in said orifice.

2. A wheel comprising a metallic rim, a plate fitting within said rim, and removably secured at its outer portion thereto, said plate having a central orifice, a hub fitting within said orifice and having a flange 95 against which said plate is seated, means for 100

securing said plate and flange together, said plate having radial grooves therein, and said hub flange having lugs to enter said grooves.

3. A wheel comprising a sheet metal rim having an outwardly projecting rail-engaging flange on one edge and an inwardly turned flange at its opposite edge, a metal disk fitting within said rim and having a central opening, a hub fitting within said

opening and secured therein, said disk extending diagonally from said hub to said inwardly turned flange and having a surface fitting the surface of said flange, and means securing said disk and flange together.

In witness whereof, I have hereunto set my hand this 27 day of January 1923.

WALTER F. KASPER.
